CLAIM

The ornamental design for a snap-on cap, as shown and described.

DESCRIPTION

FIG. 1 is a top-right front perspective view of a snap-on cap in a closed position showing my new design;
FIG. 2 is a front side view of the snap-on cap in the closed position of FIG. 1.

FIG. 3 is a rear side view of the snap-on cap of FIG. 1;
FIG. 4 is a right side view of the snap-on cap of FIG. 1;
FIG. 5 is a left side view of the snap-on cap of FIG. 1;
FIG. 6 is a top plan view of the snap-on cap of FIG. 1; and,
FIG. 7 is a top-left front perspective view of the snap-on cap in the fully open position of FIG. 1.

In FIG. 7, the cap is fully open. The cap may be opened any extent between the closed position of FIG. 1 and the fully open position of FIG. 7.
